(57) **CLAIM**

The ornamental design for a fidget toy, as shown and described.

DESCRIPTION

FIG. 1 is a front perspective view of a fidget toy, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged detail view of area 9 in FIG. 7.

The evenly broken lines in the drawings disclose unclaimed portions of the fidget toy; the dash-dot broken lines disclosed in FIGS. 7 and 9 depict unclaimed bounds of the isolated/enlarged views; the broken lines form no part of the claimed design.
